UNITED STATES PATENT OFFICE.

HENRY B. KEIPER, OF LANCASTER, PENNSYLVANIA.

DESIGN FOR A STAND FOR ROTARY BLOWERS AND FORGES.

SPECIFICATION forming part of Design No. 34,880, dated July 30, 1901.

Application filed June 8, 1901. Serial No. 63,806. Term of patent 14 years.

To all whom it may concern:

Be it known that I, HENRY B. KEIPER, a citizen of the United States, residing at Lancaster, in the county of Lancaster and State of Pennsylvania, have invented and produced a certain new and original Design for Stands for Rotary Blowers and Forges; and I do hereby declare the following to be a full, clear, and exact description of the invention, such as will enable others skilled in the art to which it appertains to make and use the same.

In the accompanying drawing, which forms a part of this specification, I have illustrated a perspective view of a stand for a rotary blower embodying my new design.

As shown in said drawing, the said stand (denoted by the letter A) consists of a structure having the general appearance of a tripod, the three legs *a* of which have the appearance of entering sockets *b*, depending from the angular headpiece or table B, which is shown with a central aperture *b*' to receive a correspondingly-shaped arm entered therein, on which may be supported the operative parts of the blower, and with a set-screw *b*² tapped through one side of a pendent portion of the base. The said legs are shown extending for

a considerable portion of their length in vertically substantially parallel planes and terminating in outwardly flaring or divergent 30 portions providing the feet *a*' to rest upon the floor or any suitable support therefor.

As will be seen, the leading or material feature of my new design resides in a tripod-like structure the legs of which for the greater 35 portion of their length extend in substantially vertical parallel planes to their junction, with a socketed headpiece of angular form and centrally apertured, while the lower portions of said legs are flared outwardly, substantially as shown.

Having thus described my invention, what I claim as new, and desire to secure by Letters Patent of the United States, is—

The design for a stand for rotary blowers 45 and forges, substantially as shown and described.

In testimony whereof I affix my signature in presence of two witnesses.

HENRY B. KEIPER.
